UNITED STATES PATENT OFFICE

165,918

GAME BOARD

Arthur Gorman Hobbs, Baltimore, Md., assignor
of one-tenth to Melvin S. White

Application July 16, 1951, Serial No. 15,892

Term of patent 7 years

(Cl. D34—5)

To all whom it may concern:

Be it known that I, Arthur Gorman Hobbs, a citizen of the United States, residing at 3804 Woodlea Avenue, Baltimore, State of Maryland, have invented a new, original, and ornamental Design for a Game Board, of which the following is a specification, reference being had to the accompanying drawings, forming a part hereof.

The figure is a plan view of a game board embodying my new design. The board has a conventional thickness and its other side (not shown) is substantially plain.

The lining on the drawing is for contrasting colored areas, the hedge on either side of the simulated track being gray.

I claim:

The ornamental design for a game board, as shown and described.

ARTHUR GORMAN HOBBS.
